UNITED STATES PATENT OFFICE.

CARL GUSTAV THROBJÖRN SALENIUS, OF BOHUS, SWEDEN, ASSIGNOR TO GESELLSCHAFT FÜR TECHNIK M. B. H., OF BERLIN, GERMANY.

CENTRIFUGAL MACHINE WITH DIRECT MOTOR DRIVE.

Application filed June 3, 1924. Serial No. 717,636.

To all whom it may concern:

Be it known that I, CARL GUSTAV THROBJÖRN SALENIUS, a subject of the King of Sweden, residing at Bohus, Sweden, have invented certain new and useful Improvements in Centrifugal Machines with Direct Motor Drives, of which the following is a specification.

My invention relates to an improved centrifugal machine including a motor, preferably an electric motor, directly connected therewith, and more particularly to a machine of the stated kind for separating or treating liquids.

There are two types of centrifugal machines having a direct motor device and adapted for separating purposes, which are clearly distinguished from each other as regards the particular purpose and the mode of operation. The one type is constructed and intended for use in separating moisture or water from solid materials or goods, chemical substances, granular or lumpy materials, textile goods and the like, inclusive of separating types for chemical salts. Machines of this type usually comprise a separating rotary cylinder of a relatively large diameter and, for this reason, do not require a high number of revolutions in order to work satisfactorily. On the other hand machines of this type cannot stand high velocities, say of about 10,000 revolutions per minute, but necessarily must remain within the limits of a few hundred to 35 at the highest 2000 revolutions per minute for the reason that any greater speed will produce heavy jerks and shocks in the machine and damage the same on account of unequal location and uneven weight of the solid material in the revolving cylinder or drum which cannot be avoided.

The other type of the said centrifugal machines mainly serves for separating liquids of different specific gravity or liquids from solid matter contained therein in the form of minute particles; in particular machines of this type are used for creaming off milk, purifying oils and the like and the rotary cylinder or vessel must be given a speed by far in excess of that of the first named type or class, the speed amounting, generally speaking, to 6000 to 12000 revolutions per minute, depending upon the size of

the machine. As unequal location or distribution of the matter treated in the machine practically cannot occur owing to the liquid state of said matter, difficulties of constructing a machine of this class mainly reside in avoiding any differences of weight in the body of the machine itself and particularly any vibrations and quick oscillations, which would readily set in owing to the high speed of the machine, in order to prevent at the same time the machine from damage and precious wear, to ensure a reliable operation and to obtain a correct centrifugal action or separation of the constituents of the treated liquid. For it has been found that in order to accomplish this purpose the machine must be so constructed and arranged as to run thoroughly free from vibrations.

For the stated reasons it will be easily understood that the constructional means employed in centrifugal machines intended for running at a relatively low speed are objectionable and fail in machines of the hereinbefore stated high speeds. This is mainly due to the difference or purpose, as already intimated, further to the special construction and arrangement of the rotary drum or vessel and to the particular proportion of the masses of the drum or vessel and the motor required for treating or separating liquid substances. In quick running machines of the kind, therefore, constructional means, such as rigid bearings in combination with springs or buffers, and a high suspension of the revolving system with the rotary drum arranged at a low level are not applicable.

The object of my invention is to provide a quick running machine of the kind which is easily constructed and in which the movement of the revolving vessel is absolutely free from vibrations. With this aim in view I support the casing of the motor, on a surface of the form of an open shell, so as to be movable thereon and with the centre of gravity of the revolving system situated over and above the said supporting surface and preferably below the centre of the spherical concavity of the said shell. Further objects and advantages of the invention will be set forth in the detailed description which now follows.

The various features of my invention are

embodied in the machine diagrammatically shown on the accompanying drawing in which—

Figure 1 is a sectional view of the machine and

Figures 2 and 3 are sectional views of modifications.

The electric motor of the machine may be of any conventional type comprising a stator *a* and a rotor *c* mounted with its vertically projecting shaft *f* to directly drive the rotary drum or vessel *d*. The motor is movably supported on a bearing surface or marginal flange *e* of the frame or bed *b* of the machine and this bearing surface constitutes, in cooperation with the correspondingly shaped supporting member or disc *g* of the motor, the main feature of the invention. The bearing surface *e* is in the form of a shell the central portion of which is removed for the motor to depend therethrough, as will be clearly understood from Figure 1 of the drawing, so that the surface *e* in reality consists of an annular segment of a shell or calotte. Preferably I give the shell a spherical inner surface but any other suitable shape of geometrical nature such as a parabolic or conical form may be employed instead.

The revolving system of the machine comprises the rotor *c*, the shaft *f* and the drum or vessel *d* revolving therewith. Owing to the relatively great weight of the latter the centre of gravity of the system is situated over and above the supporting surface or flange *e*. The radius of curvature of the shell or surface *e* is relatively very great so that, in case of the preferred construction of the shell as an annular portion of a sphere, the centre of said sphere will be considerably remote over and above the centre of gravity of the system. As above stated, the motor is movably supported by the surface *e*. In order to limit the movability, however, stops or abutments may be provided on the surface *e* which are not shown in the drawing as the arrangement and operation thereof will be readily understood by persons skilled in the art without illustration.

Further resilient or elastic members, such as springs *h* or rubber pads *i*, may be inserted intermediate between the contacting surfaces of the supporting shell and the laterally projecting member *g* of the motor for the purpose of mitigating shocks that may occur on certain occasions such as a transport.

In some cases I find it advisable to provide resilient guiding means at the lower end of the shaft of the motor, or to mount the lower end of the shaft in a resilient bearing or on a suitable spring. The drum or vessel *d* is supported by the shaft of the motor and this may be advantageously done by suspending the same on the top of the

shaft by means of a rigid connection, preferably, however, the connection may be such that the drum or vessel will be adapted to freely oscillate about a point or centre that is fixed or approximately fixed with relation to the shaft.

In the latter case there are two different movements possible—apart from the revolution of the rotor and the drum or vessel—that is to say, the oscillation of the drum or vessel on and relatively to the shaft of the rotor and the oscillating adjustment of the whole of the motor about a fixed or approximately fixed point in the alignment of the axis of the motor shaft.

In operation however, a machine constructed in accordance with my invention as hereinbefore set forth does not allow the revolving system to undergo any oscillations of its own, on the contrary, the revolving parts of the machine are running without the occurrence of shocks or vibration even at highest speed. For this reason my improved centrifugal machine, although adapted and intended for use as a high speed separator for treating liquids of any suitable kind, still is of special advantage as a milk separator.

I have not attempted to explain all of the minute details of the construction of the machine, for it will be understood by those, to whom this specification is addressed, that the parts will necessarily be of the proper size and relationship, and will be properly mounted and arranged according to the tenets of machine construction, nor have I attempted to illustrate the parts in their exact sizes and dimensions as the drawing is of diagrammatic nature only and many of the parts are conventionally shown.

I find it also unnecessary to reiterate the operation of the machine, for the operation of the several parts has been described in detail. Nor does it seem necessary to burden this specification with an exposition of the many advantages which the invention possesses, for they will be apparent to those versed in the art to which this invention relates.

What I claim is:—

1. A centrifugal machine comprising a hollow frame having an annular marginal bearing flange; a supporting disc resting on said flange; a motor secured to the underside of said supporting disc and projecting into said frame; and a shaft having a vessel at its upper end rotatably supported in said disc, said disc allowing oscillation of said vessel and its shaft.

2. A centrifugal machine of the type set forth comprising, in combination, a revolving vessel, a motor mounted and arranged to directly drive said vessel, a frame for the reception of the said motor, and annular bearing flange on the said frame for moy.

ably supporting the said motor, and resilient means on the said bearing face for yieldingly supporting the motor.

3. A centrifugal machine of the type set forth comprising, in combination, a revolving vessel, a motor mounted and arranged to directly drive said vessel, a vertical motor shaft connected to and carrying the said vessel loosely so as to allow the latter to os-

cillate, a frame for the reception of the said motor, an annular bearing flange on the said frame for movably carrying the said motor, and resilient means on the said bearing face for yieldingly supporting the said motor.

In testimony whereof I affixed my signature.

C. G. TH. SALENIUS.
